UNITED STATES PATENT OFFICE.

CHARLES H. SHERMAN, OF NORTH ATTLEBORO, MASSACHUSETTS.

DESIGN FOR A BRACELET.

Application filed June 24, 1922. Serial No. 2,809. Term of patent 14 years.

To all whom it may concern:

Be it known that I, CHARLES H. SHERMAN, a citizen of the United States, residing at North Attleboro, in the county of Bristol and State of Massachusetts, have invented a new, original, and ornamental Design for Bracelets, of which the following is a specification, reference being had to the accompanying drawings, which form a part thereof.

I provide two strands of gold, silver or alloy wire between which is inserted a

beaded chain consisting of alternately arranged elongated and round beads. The strands are loosely bound together by means of a plain guard.

The figure is a perspective view of a bracelet showing my new design, the hand of an individual being illustrated in dotted lines.

I claim:

The ornamental design for a bracelet as shown and described.

CHARLES H. SHERMAN.
